AIR-HEATING FIREPLACE

Edward T. Kelley and Guy F. Fenton,
Clearfield, Pa.

Application April 1, 1941, Serial No. 386,340

6 Claims. (Cl. 126—121)

Our invention as described hereinafter in detail relates to an air-heating fireplace found to have exceptional advantages in manufacture, installation and service. It has been previously found that the space immediately around the walls of a fireplace may be utilized as passageways for indirectly heating currents of air.

It is an object of our invention to produce a fireplace built up from sections of hollow fire clay, iron, steel, terra cotta or other fire-resistant materials. Such sections may be designed for interfitting assembly and may permit the construction of a fireplace having varying dimensions. Thus the width of the fireplace may be varied by change in the rear sections only and the depth of the fireplace may be varied by the replacement of side sections by larger ones.

The interfitting character of the sections permits the ready replacement with a new section of any which may have become unserviceable.

A further object of our invention is to construct the fireplace of plastic material such as fire clay or the like which will have inherently poor conduction of heat. In this way the fireplace may be assembled in the structure of the house with less protection required against the risk of overheating than would be the case if the material were metallic or a similar good conductor of heat.

An additional object of our invention is to improve the manner in which currents of heated air are created for warming the room apart from the radiation from the front of the fireplace.

An incidental object of the invention is to separate the air passageways of the two sides of the fireplace so that the heating effect on each side will be separate from that on the other side. Thus the delivery of heated air will necessarily occur on the side in which the air is received. Also it will permit adjustment of the amount of heated air by closing the passageways on one side only thus making the air passageways on that side into dead air spaces.

The particular arrangement of the air passageways is such as to baffle or retard the flow of air being heated so that its absorption of heat during the travel through the device will be increased.

In the construction of the individual sections of our fireplace, extra strength is obtained by using the walls of the passageways as reinforcements.

Note is made that the assembled fireplace has the same area at its top as at its ground line, 55

so that it will conform to the smoke box above without the necessity of further adjustment.

Other and further objects of our invention will be evident from the detailed description which follows of our preferred embodiment in which

Fig. 1 is a perspective view of the fireplace with parts broken away;

Fig. 2 is a plan view of the rear base member;

Fig. 3 is a front elevation of the same with parts broken away on the line 3—3 of Fig. 2;

Fig. 4 is a plan view of the rear top member;

Fig. 5 is a front elevation of the same partly in section on the line 5—5 of Fig. 4;

Fig. 6 is a vertical cross-section on the line 6—6 of Fig. 5;

Fig. 7 is a front elevation of the left base member and

Fig. 8 is a front elevation of the left top section.

We have found that it is feasible to construct our fireplace entirely from ceramic material such as fire clay, terra cotta or similar compositions.

These have the advantages of being fire-resistant and also are approved building materials for surrounding flues and the like. By constructing the several sections of our fireplace in this manner, they can be individually cast or molded and separately fired. They can be given accurate measurements. Thus they may be fitted together and cemented to form a unitary self-sustaining fireplace.

Referring to Fig. 1 it will be noted that the structure comprises a lower back section 11 upon which an upper back section 12 rests. Lower side sections 13 and 14 extend forwardly from the left and right respectively of the lower base section 11. A suitable angle between the front walls of the section is selected and this determines the shape of the interfitting edges of the several parts.

Resting upon the lower side section 13 is upper side section 15 on the left while upper side section 16 on the right rests above lower side section 14.

It is to be understood that the several sections are cemented together with fire-resistant cement so that smoke will not percolate into the air 50. passageways and also that the passageways will vent only through the exit or outlet ports.

The customary damper will be pivoted across the top of the upper side sections 15 and 16 in front of the upper back section 12.

A smoke box preferably in the form of a pyra-

mid will rest upon the upper sections 12, 15 and 16 and connect the fireplace to a suitable flue.

The lower back section 11 is constructed in the manner shown in Figs. 2 and 3. There is an outer wall 17 and a parallel front wall 18, the ends of which are rabbeted to receive the walls of the side sections. The top wall 19 connects the walls 17 and 18 and has its edges sloped back at an angle determined by the flare of the side sections 13 and 14. A corresponding bottom 20 runs from side to side of the section. Centrally the section has a vertical partition 21 which connects the top, bottom and front and rear walls. Running outwardly from the partition 21 on each side thereof is a slightly inclined partition 22.

Intermediate the bottom 20 and the partition 22 is a baffle 23 which is inclined upwardly toward the center partition but is spaced therefrom to form a passageway.

The outer edges of the top, bottom and both partitions are in a common vertical plane as indicated.

Cooperating with the lower back section are lower side sections 13 and 14. The lower side section 13 is shown in detail in Fig. 7. Here there is an outer wall 24 and this is cut away to form an inlet port 25 (see Fig. 1).

The end wall 26 extends the full length from the bottom 27 to the top of the section. A top 28 is spaced from the end wall 26 to form an outlet port 29. The wall 30 extends over the entire front of the section with the exception of a small vertical area at the right which is intended to register with the open edge of the rear section 11. A lower partition 31 extending between the rear wall 24 and the front wall 30 also intersects the end wall 26 above the inlet port 25. At its opposite end it fits beyond the baffle 23 of the rear section as shown in Fig. 1.

In like manner an upper baffle 32 extends from the rear edge of the section 13 forwardly to the outlet port 29. It inclines slightly upwardly and forms a continuation of the partition 22 of the rear section.

The right lower side section is similar to the left lower side section just described with the exception that the arrangement of the ports, partitions and baffles is reversed.

The lower rear section 11 supports an upper rear section 12. The back wall 33 of the upper section is in the same vertical plane with the back wall 17. However, the front wall 34 slopes forward to form the throat of the chimney in the usual manner.

The top 35 of the section thus forms a smoke shelf as shown in Fig. 4.

The rear wall 33 is suitably rabbeted at its ends to fit the side sections. The bottom wall 36 of the section conforms in shape to the top wall of section 11 as shown in Fig. 2.

A vertical central partition 37 extends between the bottom, top, front and rear walls.

A baffle 38 extends between the front and rear walls on each side of this section inwardly toward the center partition but spaced therefrom to form a passageway. As shown in Fig. 5 this baffle is sloped up and back.

Above the baffle 38 a partition 39 extends outwardly from the center partition 37. The partition 39 is sloped up and forwardly as shown in Fig. 5.

The outer ends of top, bottom, baffle 38 and partition 39 are in a common vertical plane sloped backwardly as shown in Fig. 4 in order to

fit the side of the corresponding upper side sections.

The upper left side section is shown in Fig. 8 to consist of a vertical outer wall 40 which is cut away at one corner to form the outlet port 41. The top 42 extends over the outlet port 41 and contacts the front end 43.

The opposite or rear end is opened while a bottom 44 extends forwardly to an inlet port 45 registering with the outlet port 29 of the lower side section.

The front wall 46 fits from the top 42 to the bottom 44 and inwardly from the front end 43 to a sloping edge determined by the forward slope of the throat or front 34 of the upper rear section.

A partition 47 slopes to the rear from the front end 43 to the opposite free edge of the section. Here it contacts with the rear wall 33 of the upper rear section and registers with the edge of the baffle 38.

A similar partition 48 extends upwardly and forwardly from the rear free edge of this section to the corner of the port 41. A short wall 49 rises vertically from the front edge of partition 48 to the top 42. The partition 48 registers at its rear with the partition 39 of the upper rear section.

The right upper side section 16 is similar to the one just described with the exception of the reverse arrangement of the several parts.

Each section of the fireplace is constructed separately by molding, casting or other mode of fabrication. It is then fired. This mode of manufacture can be done at a central point or may be carried out at the locality where it is intended to supply these fireplaces. Risks and high cost of transportation may thus be minimized.

The several sections have interfitting portions by which they may be interchangeably assembled or new sections inserted to take the place of any others which may become unserviceable. The assembly may be done by relatively unskilled labor as it requires only the application of furnace cement. The arrangement and spacing is determined by the form of the sections themselves. A bricklayer can lay it up without measurements and every piece will immediately fit in its proper place. After the fireplace is set up and cemented, a brick or stone facing to match the room or architecture of the building, can be built around it.

By assembling the lower tier of sections and then mounting the upper tier over them, it is easy to see that all joints are smoke tight. The completed structure is rigid, self-supporting and also capable of supporting the customary smoke box.

Heat from the fire will pass through the inner walls of the sections and heat the air in the connecting passageways. By reason of the baffling, the air on each side of the fireplace is independently heated. The air will be given the maximum amount of heat before it is permitted to escape into the room from the port 41. However, by blocking either inlet port 25, the air passageways on that side will be closed and become dead air spaces.

The construction of the several sections with the intermediate partitions and baffles serves to give added strength and to retain the desired form through the process of manufacture and firing. The added strength is a feature of the completed device.

While we have described above in detail the

preferred form of our invention, it is to be understood that various changes in minor details including materials, proportions and the like are possible within the scope of the appended claims.

What we claim is:

1. A fireplace comprising a hollow back with a vertical partition on its center line and having open ends and transverse baffles extending inwardly therefrom to points spaced from the vertical center line of the back to form interconnected passageways, upper and lower side sections open on the ends adjacent the back, each side section being cut away at its base to form an inlet port and being cut away at its upper portion to form an outlet port and baffles in said side sections forming passageways connecting said ports with the passageways in the back.

2. A fireplace comprising a hollow back having a vertical median partition, open ends and horizontal baffles forming passageways inwardly therefrom to the partition, upper and lower hollow side sections open on the ends adjacent the back, each side section being cut away at its base to form an inlet port and being cut away at its upper portion to form an outlet port and baffles in said side sections forming transverse passageways in said side sections connecting said ports with the passageways in the back.

3. A fireplace comprising a hollow back having a vertical median partition and open ends, an inclined partition extending from the vertical partition to each open end, an inclined baffle spaced beneath each inclined partition, upper and lower hollow side sections open on the ends adjacent the back, each side section being cut away at its base to form an inlet port and being cut away at its upper portion to form an outlet port and partitions in said side sections defining passageways in said side sections connecting said ports with the passageways in the back formed by said baffles and partitions.

4. A fireplace comprising a hollow back formed of two superposed sections, each section having a

vertical median partition and open ends, an inclined partition extending from each vertical partition to each open end, an inclined baffle spaced beneath each inclined partition, hollow upper and lower side sections open on the ends adjacent the back sections, each side section being cut away at its base to form an inlet port and being cut away at its upper portion to form an outlet port and partitions in said side sections defining passageways in said side sections connecting said ports with the passageways in the back formed by said baffles and partitions.

5. A fireplace comprising a back formed of superposed upper and lower hollow sections, each section having a vertical median partition and open ends, an inclined partition extending from each vertical partition to each open end, an inclined baffle spaced beneath each inclined partition, upper and lower hollow side sections open on the ends adjacent the back sections, each side section being cut away at its base to form an inlet port and being cut away at its upper portion to form an outlet port and partitions in said side sections defining passageways in said side sections connecting said ports with the passageways in the back formed by said baffles and partitions.

6. A fireplace comprising a hollow back of ceramic fire-resistant material and having open ends, an integral inclined partition extending inwardly from each end, an integral inclined baffle beneath each partition, hollow side members of the same material open on the ends adjacent the back, each side member being cut away at its front end to form upper and lower ports, and inclined partitions in each side member extending from front to rear to define connecting passages between the front ports and the passageways in the back formed by said first named partitions and baffles.
